FLUID MIXING DEVICES

Clifford L. Barker, Cheltenham, England, assignor to Walker, Crossweller & Company Limited, Cheltenham, England

Filed Feb. 25, 1958, Ser. No. 717,501

Claims priority, application Great Britain Feb. 26, 1957

3 Claims. (Cl. 236—12)

This invention has reference to fluid mixing devices of the kind wherein two separate streams of fluid at different temperatures (such as hot water or steam and cold water) are adapted to be fed into the device through corresponding inlets and, after passing through a valve which determines the relative proportions of the two streams flowing therethrough, to be mixed in a chamber in which a thermosensitive element is housed so that the said element is influenced by the temperature of the resulting mixture and, as a consequence, is adapted to alter the setting of the valve and thereby vary the said relative proportions should the temperature of the mixture depart from a preselected value.

Mixing devices of this kind are well known and are in wide use for supplying water at a desired temperature to wash hand basins, baths, showers and similar sanitary installations. However, should a device develop a fault as a consequence of corrosion, excessive wear, the presence of solid foreign matter which prevents the proportioning valve from functioning correctly, or for any other reason, the installation may be put out of commission until it is possible to obtain the services of a plumber or other skilled workman capable of remedying the fault. In many instances, such services are not readily available or, if they are available, it may not be possible for the workman to correct the fault quickly and easily, much to the annoyance and inconvenience of the user of the device, particularly if the said device is installed in the sanitary installation of a private dwelling house.

The principal object of the present invention is to overcome or minimise the possibility of a mixing device being put out of commission for any considerable period as a consequence of the development of a fault in its operative component parts.

The above and other objects and advantages of the invention will become apparent from the following detailed description taken in connection with the accompanying drawing in which:

Figure 1 is a sectional elevation of a fluid mixing device, and

Figure 2 is an exploded view, partly in section, of the device shown in Figure 1.

The device shown in the drawing is intended for mixing a stream of hot water with a stream of cold water to provide a mixture which is at any preselected temperature within maximum and minimum limits.

The device comprises a base 1 having two coaxial and tapped inlet passages 2, 3, of which the outer ends open to opposite sides of the base so that a cold water supply pipe is adapted to be connected into one of the said passages and a hot water supply pipe is adapted to be connected into the other passage. The base is also formed with at least one tapped mixture discharge orifice (not shown) into which a tap or faucet or another pipe (also not shown) is adapted to be connected.

The crown of the base is of cup shape and an annular lip 4 projecting upwardly from and located concentri-

2

cally of the floor of the cup, forms a well 5 in the bottom of which there is a concentric port 6 which opens to the interior of the well and the inner end of the passage 2. A second port 7 formed in and eccentrically of the bottom of the well, opens into the interior of the well and the inner end of the other passage 3.

The mouth of an inverted cup-shaped cover 8 sockets into the mouth of the base 1 and the cover is detachably secured to the said base in any known and convenient manner (not shown). The interiors of the cup-shaped crown of the base and of the cover form a mixing chamber 9 from which the discharge orifice opens and in which a unit, comprising a fluid-proportioning valve 10 and a thermosensitive element 11, is detachably mounted.

15 The fluid proportioning valve consists of a cylindrical spigot 12 which serves as the inner and non-rotatable member of the valve and a ported sleeve 13 which is a rotatable fit around the spigot and serves as the moveable member of the said valve.

20 The spigot is provided at and around its lower end with an enlarged diameter portion 14 of which the upper edge serves as a seat for the adjacent lower edge of the sleeve 13.

25 The lower end face of the spigot is provided with a co-axial extension 15 and a blind fluid inlet passage 16 formed in and concentrically of the said extension, extends through the extension and along the spigot to a position just beyond a first group of radial passages 17 (of which one is shown in Figure 1) extending from the said blind passage to the spigot periphery. In addition, a blind annular fluid inlet passage 18, formed in the spigot around and concentrically to the passage 16 extends from the said lower end face where it opens into the well 5, to a position short of the radial passages 17 where it 30 communicates with a second group of radial passages 19 (of which one is shown in Figure 1) extending from the said blind passage to the spigot periphery. The two groups of radial passages are spaced apart lengthwise of the spigot, the passages of each group are located in a common plane transverse of the spigot and are spaced at equiangular distances apart, and each passage in one group is located between two passages of the other group. Further, the valve sleeve 13 is formed with two groups of ports 20 and 21 each group being located in the same 40 transverse plane as a corresponding one of the two groups of radial spigot passages; the relative arrangement of radial passages and ports is such that when (as shown in the drawing) each port 21 is in register with the outlet end of a corresponding radial passage 19 of the passage group in the same plane, all the ports 20 are completely out of register with the radial passages 17 so that water supplied to the device through the inlet passage 3 may flow at full bore into the chamber 9, whereas the flow of water through the inlet passage 2 is cut off. However,

45 rotary movement of the valve sleeve by the thermosensitive element 11, takes the group of ports 21 gradually out of register with their corresponding radial passages 19, and as this takes place the ports 20 commence to move into register with their corresponding passages 17 with the result that the flow of water through the inlet passage 2 is initiated and increased gradually at the expense of the flow through the outlet passage 3 which is 50 gradually reduced until it is cut off.

A peripheral groove is formed in and around the enlarged diameter portion 14 of the spigot, another peripheral groove is formed in and around the co-axial projection 15 and a resilient ring 22 and 23 respectively is accommodated in each groove, the said rings having cross-sectional diameters greater than the depths of their respective grooves.

55 A spindle 14 formed integrally with the spigot, projects from and concentrically of the upper end face of

the said spigot, and a peripheral groove 25 is formed in and around the upper and free end of the said spindle.

The thermosensitive element 11 comprises two parallel spiral coils 26 and 27 wound from bimetallic strip and the innermost turn of each coil is carried upon, and secured by its extremity to, a hub 28 and 29 respectively, the said hubs being mounted around and being rotatable relatively to the spindle. The hub of the lower coil 26 is provided with two radial aligned arms 30 which seat upon the upper end face of the spigot and one of which is provided with depending tongue 30^a; this tongue engages a complementary recess in the upper edge of the valve sleeve to enable drive to be transmitted from the hub to the sleeve; the tongue 30^a extends radially inwards of the sleeve into engagement with a pocket 12^a in the upper end face and periphery of the spigot 12 thereby limiting the rotary movement of the sleeve relatively to the spigot. The other and upper coil hub 29 is formed with a concentric upwards extension 31 having a peripheral groove formed therein, the said groove also being engaged by a resilient ring 32 of greater cross-sectional diameter than its depth. The spindle enters a blind axial bore in the upper coil hub, and is secured within the said bore by two parallel pins 33 which pass through the hub tangentially to, and engage in, the spindle groove 25 so that relative longitudinal movement is prevented, but relative rotational movement is permitted, between the hub 29 and spindle 24. The outermost turns of the two coils are secured respectively to the opposite ends of a strap 34.

The pinning of the upper coil hub 29 to the spindle 24 integral with the valve spigot, the seating of the radial arms 30 upon the upper end face of the spigot, and the abutment of the lower edge of the valve sleeve upon the shoulder around the lower spigot end, ensures, first, that the several components are assembled as a single unit, secondly, that the two coils are located in selected positions along the spindle and, thirdly, that the sleeve is in a selected position along the valve spigot.

Further, the provision of the resilient rings 22, 23, around the spigot and the bored extension from the lower spigot end face, enables the spigot to make a close and fluid tight joint within a well 5 when the spigot is socketed into the mouth of the said well, and enables the projection to make a similar joint within the port 6 formed in the bottom of the well when the extension is socketed into the said port. The pinning of the upper coil hub to the spindle enables the said two fluid tight joints to be made or broken simultaneously by pushing or pulling, by hand, the upwards extension from the said hub, without imposing any strain or stress upon the bimetallic coils 26, 27, and without disturbing the relative relationship between the valve sleeve and spigot. To ensure that, when the spigot is socketed into the mouth of the well, the said spigot is unable to rotate about its axis, a pin 13^a (see Figure 2) projecting from and eccentrically of the lower end face of the said spigot, sockets into a complementary blind hole 1^a in the bottom of the well.

The resilient ring 35 in the extension 31 from the upper coil hub enables the said extension, when inserted into an aperture 35 in the crown of the cover 8 to effect a fluid tight joint with the said cover and also enables the said joint to be made or broken by a simple manual push or pull action; as shown in Figure 1 the cover crown seats upon a peripheral shoulder 36 on the hub extension 31, when the said joint is made and the cover is assembled to the base 1.

The said upwards extension 31 is of a length greater than the thickness of the cover crown and, therefore, projects beyond the said crown to the exterior of the device, where a handle or knob 37 is assembled and detachably secured thereto in any known and convenient manner.

Should any fault develop in the proportioning valve 10 or the thermosensitive element 11, it is only necessary to disconnect the cover from the base of the mixing device

whereupon by pulling the cover, the valve-and-element unit may be withdrawn from engagement with the well 5 and the port 6; then after dismantling the knob or handle 37 from the hub extension 31, the said unit may be removed from the cover by pushing upon the external end of the said extension. A reversal of these operations, using a replacement unit which is in good working order, restores the device to its normal operative condition.

From the foregoing description, taken in connection with the accompanying drawing, it will be apparent to those skilled in the art that I have devised a novel, efficient and simple type of unit which includes a proportioning valve and thermosensitive element and which is capable of being installed in a fluid mixing device, and of being replaced in the event that any fault develops in the unit, in a simple, speedy and efficient manner even by unskilled persons. Whilst the said description and drawing describes and illustrates respectively a typical and practical embodiment of my invention, it is to be understood that departures may be made therefrom, within the scope of the invention, which is not to be limited to the details disclosed herein, but is to be accorded the full scope of the claims so as to embrace any and all equivalent mixing devices.

25 What I claim is:

1. A fluid mixing valve comprising a hollow base having two fluid inlet passages, a hollow cover removably seated on said base, a proportional mixing mechanism removably seated in said base and communicating with said passages, the interior of said base and cover forming a mixing chamber, a control handle removably connected to said cover, a spindle detachably connected between said handle and said mixing mechanism for varying the selected temperature of the fluid mixture, thermosensitive means in said mixing chamber connected to and operatively associated with said mixing mechanism for automatically compensating for changes in temperature in the mixing chamber, said mixing mechanism, spindle and thermosensitive means constituting a single unit removable with said cover, a spigot around which a valve sleeve is mounted for rotational movement only, an axially bored extension projecting from and concentrically of one end of the spigot and making a fluid-tight fit within a complementary port in the bottom of a well formed in the crown of the said base, the said port communicating with one of the fluid inlets in the base and wherein the said spigot end sockets into and makes a fluid tight fit within the well, has an annular passage opening to the interior of the well and communicating with the one of said inlets in the base through an eccentric port in the bottom of the well.

2. A device as claimed in claim 1, wherein the spigot end which sockets into the well is of larger diameter than the remainder of the spigot and the upper edge of the said larger diameter end provides an annular seat for the adjacent edges of the valve sleeve.

3. A device as claimed in claim 1, the spigot extension and the adjacent end of the spigot are each formed with a peripheral groove and a sealing ring accommodated in the said groove effect respectively fluid tight joints between the spigot and the wall of the well and between the spigot extension and the port in the bottom of the said well.
